Attorney.

UNITED STATES PATENT OFFICE.

ROBERT E. LARSON, OF SAN DIEGO, CALIFORNIA.

MUSICAL-INSTRUMENT RACK.

Application filed July 25, 1922. Serial No. 577,312.

To all whom it may concern:

Be it known that I, ROBERT E. LARSON, a citizen of the United States, residing at San Diego, in the county of San Diego and State of California, have invented a new and useful Musical-Instrument Rack, of which the following is a specification.

My invention relates to improvements in musical instrument racks, on which there are provided supports on which a number of musical instruments may be placed so that any one of the instruments may be quickly placed thereon by the player and another put into use by him. It is of particular value to the player of reed instruments as the liability of having the reed injured by falling or being dropped, makes it necessary to have some such device for the protection of the instrument, and at the same time have the instruments so disposed that the player can quickly change instruments in the playing of selections where the change from one instrument in the same selection is required to be made so as not to interfere with the work of the play.

I attain these objects by the device illustrated in the accompanying drawing, in which:

Figure 1 is a front elevational view of my device; Fig. 2 is a sectional plan view thru line 2—2 in Fig. 1; Fig. 3 is a sectional plan view thru line 3—3, and Fig. 4 is an enlarged broken sectional view of the top support member.

Similar characters refer to similar parts throughout the several views.

The base *a* and the adjustable upright *b* form the principal parts of my invention.

The adjustable upright *b* consists of the two members *b*¹ and *b*². The member *b*¹ is hollow and is mounted in the base *a* at *a*¹. The member *b*² is slidably mounted in member *b*¹ and is adapted to be adjusted to change the length of the member *b*. The member *b*² is provided on its upper end with a horizontal portion 3 on each end of which is a small upwardly curved portion 4, which is off-set on the ends of the portion 3 so as to provide a shoulder 5. In the upper end of the member *b*¹ there is provided a set-screw *g* which is adapted to engage and hold the member *b*² in position in the member *b*¹. The supports *c* are each provided at one end with a loop 6 which adapts it to be adjustably mounted on the upright member *b*¹, and each is provided with a set-screw 7

which is adapted to engage and hold said member *c* in position on said member *b*¹. The supports *c* are also each provided with a curved portion 8 which will be hereafter described.

A member *h* is provided on its one end with a loop 9 which adapts it to be mounted on member *b*¹ and is provided with a set-screw 10 which is adapted to engage and hold it in position on the member *b*¹ where it is mounted between the supports *c*. This member *h* is also provided with an elongated portion 11 which will be described more fully hereafter.

The base *a* is provided on its surface with a number of supports *d*. These supports *d* are pyramidal in shape and are firmly mounted on said base *a*, and are of a size to suit the instrument to be supported thereon.

The rack shown in the drawing is designed to support two saxophones and three clarinets, but it may be enlarged or modified to accommodate a larger number of instruments, or instruments of different kinds.

The curved portion 8 of the support *c* is adapted to act as a rest for a saxophone or other instrument not shown in the drawings, and the curved portion 4 of the portion 3 is adapted to enter the snap-ring of said saxophone or other instrument and support the same thereon by letting said snap-ring rest in said curved portion and against said shoulder 5. The projecting portion 11 of the member *h* serves to keep the two instruments suspended on the portion 4 from coming in contact with each other as is obvious from the position of the members *c* and *h* as shown in Fig. 3, of the drawings.

The members *d* are each adapted to provide a support for a clarinet or other instrument not shown in the drawings, by placing the bell-shaped end of the said instrument over the support *d* and letting said bell-shaped end rest on the base *a*. It is thus plainly shown that by the use of the device shown and described there is provided an instrument rack which holds a number of instruments in a compact form and convenient position for the performer to quickly change from one instrument to another, and which provides a secure place for the instruments to rest and which prevents the instrument from falling and becoming injured thereby.

What I claim is:

An instrument rack comprising a base

member, an upright member mounted on said base member, an adjustable member provided at one end with a horizontal portion with a plurality of curved instrument support portions each off-set on said horizontal portion, adjustably mounted in said upright member, adjustable support members mounted on said upright member, and a separating member mounted on said up-

right member between said two last mentioned support members.

In testimony whereof, I have hereunto subscribed my name in the presence of two subscribing witnesses.

ROBERT E. LARSON.

Witnesses:

E. E. RODABAUGH,
ALMA WOODRUFF.
